UNITED STATES PATENT OFFICE.

RUSSELL F. TRIMBLE, OF ELIZABETH, NEW JERSEY, ASSIGNOR TO WESTERN ELECTRIC COMPANY, INCORPORATED, OF NEW YORK, N. Y., A CORPORATION OF NEW YORK.

JIG EMPLOYED IN THE CONSTRUCTION OF ELECTRODES.

Original application filed November 2, 1918, Serial No. 261,030. Divided and this application filed April 16, 1920. Serial No. 374,419.

To all whom it may concern:

Be it known that I, RUSSELL F. TRIMBLE, a citizen of the United States, residing at Elizabeth, in the county of Union and State of New Jersey, have invented certain new and useful Improvements in Jigs Employed in the Construction of Electrodes, of which the following is a full, clear, concise, and exact description.

10 The invention relates to electrode structures which may be employed in an electrical discharge device such as a thermionic device of the audion type.

One type of audion employs a filamentary 15 cathode, a grid at each side of the cathode and a plate or anode surface adjacent each grid. The two grid electrodes, and the same is true of the two plate electrodes, are electrically connected together inside or outside 20 of the evacuated container. A stronger and more compact arrangement of the double electrodes is provided according to the present invention, wherein the double electrode is provided in the form of a unitary structure. This has been applied to the manufacture 25 of the grid or screen electrode which specifically is composed of two parallel U shaped side wires, parallel cross wires extending from one U to the other and at right angles thereto. This grid is claimed and described in application Serial No. 261,030, filed November 2, 1918, for electrodes and their construction, of which this is a division.

30 Another feature of the invention resides in the manufacture of double electrodes. This feature is described and claimed in application Serial No. 374,418, filed April 16, 1920, which is a division of application Serial No. 261,030, filed November 2, 1918, for electrodes and their construction. This grid is made by providing an extended electrode surface which is bent upon itself in such a fashion as to provide the desired number 35 of electrode surfaces.

A jig, which comprises the feature of this invention, is made use of in the manufacture of the grid electrode. This jig may be employed for making not only single grid electrodes, but it is particularly useful in the manufacture of a plurality of double grids, all of which may be made practically at the same time and in one continuous me-

chanical operation. On each of a plurality of flat jig faces are laid parallel wires which are to form the sides of the grid. The cross wires are formed by winding a wire across the side wires, the intersections being welded or otherwise fastened. The resulting composite structure is divided to form the required plurality of electrode surfaces.

Referring to the drawings for further details of the invention, Fig. 1 discloses in perspective a jig that may be employed in the manufacture of the electrode.

Figs. 2, 3 and 4 illustrate a grid electrode in various stages of its manufacture.

Fig. 5 illustrates diagrammatically a lathe that may be employed for revolving the jig shown in Fig. 1.

The top face 1 and the bottom face 2 of the jig 3, illustrated in Fig. 1, are constructed the same, the top face being provided with notches 4 and 5 that receive the longitudinal extending wire 6 which is to form one of the side wires in the grid. This wire 6 is continued across the face 2 as illustrated in dotted lines. A similar side wire 7 is also provided and is continued across both faces of the jig. The wires 6 and 7 may be held in the position shown by having their ends twisted or in any other suitable manner. Each edge of each face of the jig is provided with grooves 8 which are adapted to receive the wire 9 which is wound around the jig and across both faces thereof to provide the cross wires of the grid. The winding process may be performed by hand or preferably the jig is supported in a lathe such as conventionally represented in Fig. 5, in order that it may be rotated while the wire 9 is wound thereupon. It will be noted that the wire 9 in passing from the front grooved edge of the lower face to the front grooved edge of the upper face is offset, a similar offset being unnecessary at the other edge. This makes it possible for the wire 9 to cross always at right angles to the side wires 6.

After the wire 9 has been wound upon the side wires as shown, the wires where they intersect are suitably fastened together, for instance, by welding. That portion of the wire represented by 10 at the middle of the jig is not welded to the cross wires, the vacant portion at the middle of the jig being

provided in order that room may be had for forming the arch 11 which integrally connects the two grid surfaces as shown in Figs. 3 and 4. The reinforcing wires shown at 34, 35, 36 and 37 Fig. 2 may be cut to approximately the proper length, laid across the side wires 6 and 7 Fig. 1 and welded thereto, while the wires 6, 7, 34, 35, 36 and 37 are shown heavier than the cross wire 9, 10 these may all be of the same size or the cross wires 9 may be larger than the other wires. After the intersections of the cross and side wires have been welded a suitable cutting tool, such as a pair of scissors, may 15 be passed along a groove 12 and a similar groove 13 at the other edge of the jig in order to cut the wire 9 along these grooves. The side wires 6 and 7 are also cut at the ends of the jig. This releases two double 20 grid surfaces somewhat of the form shown in Fig. 2. After trimming the ends of the cross wires 9, which project beyond the side wires 6 and 7, the resulting electrode may be suitably bent into the shape shown in Fig. 25 3 and for the purpose the machine shown in my said copending application Serial No. 374,218 may be employed.

To further strengthen the grid structure the projecting end 28 of the side wire 6 may 30 be welded to the adjacent projecting end 29 as shown at 30 in Fig. 4. The other two projecting ends of the side wire 7 may be similarly welded.

It will be apparent that the grid electrode 35 shown in Fig. 4 is a rigid compact structure, the side wires of which are U shaped, the cross wires extending from the leg of one U to the corresponding leg of the other U.

The electrode shown in Fig. 4, is particularly adapted to be employed as a double grid electrode in a device of the audion type 40 as shown in my said copending application Serial No. 261,030, wherein the grid electrode has one surface located between the 45 cathode and one plate of the double anode and the other grid surface extending be-

tween the cathode and the other plate of the anode.

What is claimed is:

1. A jig comprising front and back plane faces each adapted to receive longitudinally extending wires, the edges of said faces being serrated in planes perpendicular to said wires, and a groove between adjacent serrated edges. 50

2. A jig comprising a member having smooth faces, each of said faces being adapted to receive longitudinally extending wires, and means on said jig for positioning the convolutions of a wire wound across said 60 longitudinally extending wires at right angles thereto.

3. A jig comprising a member having plane faces, each of said members being adapted to receive longitudinally extending wires, each of said faces having notches in its edges for positioning the convolutions of a wire wound across said longitudinally extending wires at right angles thereto. 65

4. A jig comprising a member having opposed parallel smooth faces, each of said faces being adapted to receive longitudinally extending wires, the edges of each of said faces being notched for positioning the convolutions of a wire to be wound across said 75 longitudinally extending wires, said notches being so disposed that said wire crosses said longitudinally extending wires substantially at right angles. 70

5. A jig comprising a member having plane parallel faces, each of said faces being adapted to receive longitudinally extending wires, the edges of each of said faces being notched for positioning substantially 80 at right angles to said longitudinally extending wires the convolutions of a wire to be wound across said longitudinally extending wires. 85

In witness whereof, I hereunto subscribe my name this 14th day of April A. D., 1920. 90

RUSSELL F. TRIMBLE.
